FIG.6

FIG. 7

FIG. 1 is a front perspective view of a cash register or similar article, showing our new design;

FIG. 2 is a rear perspective view thereof;

FIG. 3 is a right side elevational view;

FIG. 4 is a left side elevational view;

FIG. 5 is a front perspective view of a modified form of the cash register or similar article shown in FIG. 1;

FIG. 6 is a rear perspective view of the modified form shown in FIG. 5; and

FIG. 7 is a right side elevational view of a further modified form of the cash register or similar article shown in FIG. 1.

The undisclosed side of FIG. 5 is substantially the same in appearance as the side shown in FIG. 3.

The undisclosed side and front of the FIG. 7 embodiment are substantially the same in appearance as the side and front of FIG. 1 except for the inclusion of the extended rear housing portion, and the rear is plain in appearance.

The dominant features of our design reside in the full-line portions of the drawings.

We claim:

The ornamental design for a cash register or similar article, as shown and described.
